Cook Stove.

Patented Apr. 28, 1830.

Appl'd. 1836

Thomas Frazer, Horace Blanchard & Bennington Gill of Utica,
Letters Patent.

The Schedule referred to in the Letters Patent & making part of the same containing a description in the word of the said, Thomas Frazer, Horace Blanchard and Bennington Gill themselves of their improvement in Crooking & other Stoves.

It is to whom these presents shall come. Know Ye that we, Thomas Frazer, Horace Blanchard and Bennington Gill of the County and State of New York have invented constructed made and applied to our new and useful improvements in crooking and other stoves called "the improved Stove Damper," which improvements are described as follows: First. We make a damper of cast iron or other suitable material 13 inches long $\frac{1}{4}$ of an inch thick and $1\frac{1}{2}$ inches broad, having a flange of the same length and thickness and $1\frac{1}{4}$ inches broad as shown in figures 1, 2 & 3. of the annexed drawing marked D, which Damper is intended to be placed between the top plate and the top oven plate of the crooking Stove near the opening into the smoke pipe, in such manner that when the Damper is drawn back as shown in Figure 1. Drawing D. The flat part of the damper closes the passage which leads from the fire upon of the Stove under the bottom and around the back of the oven to the smoke pipe, leaving the passage from the fire to said pipe, along the front and over the top of the oven, open, or if the damper is pushed forward as shown in Figure 2. & 3. then the upright part of the damper closes the passage which leads over the oven, leaving that which leads under and behind it open. Or if the damper is drawn only part way back the heat and smoke will circulate through both passages at the same time to the pipe. The aforesaid damper may be raised or from time to time closed back as shown in figures marked A. & B. 1. 2. 3. other having the upright flange extending part way only along the back of the damper, and then raising it so as to meet vertical projections, extending from the sides of the stoves part way toward the middle of the top oven plate as shown in figure D. No 1. of the annexed drawing, and such other shapes and dimensions may be adopted as the

and sizes of the stoves in which they are used may require. Second It is made a damper of cast iron with suitable material 13 inches long $\frac{1}{4}$ of an inch thick and 2 inches broad having a short neck at each end to receive in holes made in the side plates of the stove as shown in figure C No 143. or in openings made in the inner sides of said plates just above the top of the oven. under this we place another flat damper sliding upon the top oven plate, of such dimensions that when drawn back against the back of the stove as shown in figure C No 1. its edge shall still remain under the edge of the revolving damper in which position it closes the lower passage to the stove pipe and permits the revolving damper to fall so as to leave the passage over the oven clear. and when said sliding damper is pushed forward so as to open the lower passage to the stove pipe, it at the same time raises the revolving damper so as to close the upper one see figure C No 3. or by being pushed only part way forward. it raises the revolving damper only part way and thus leaves both passages partially open. These dampers are all to be made of various dimensions to suit the stoves to which they are to be applied. The part of the cooking stove in which our improvement is made is that which lies between the top of the oven and the top of the stove. and it consists in the new arrangement above described. so as effectually to distribute and guide the heat when generated over or under or around the oven and to the objects or objects for which it is wanted, in such proportion, and in such lines and in such manner as may be required. This is effected by arranging the dampers or valves to close in part or whole as may be required. the passage through which the flame and heat around and the internal arrangement and construction of the above described parts, and upon the upper part of the stove. the whole being combined in such manner as to produce the desired result. We claim a combination and improvement the construction arrangement and combination of the above described dampers or valves with the interior of the top of the cooking stove and any other similar arrangement and combination of similar parts for the same pur-

is placed in the top of a stove for the purpose aforesaid, and for
this improvement we request Letter Patent.
